United States Patent Office

Des. 199,950
Patented Dec. 29, 1964

199,950

CARRYING CASE

Robert Louis Deschamps, near West Chicago, and Raymond A. Massaccesi, Chicago, Ill., assignors to Shure Brothers, Incorporated, a corporation of Illinois

Filed Sept. 18, 1963, Ser. No. 76,622

Term of patent 14 years

(Cl. D87—5)

FIG. 1

FIG. 2 is a top plan view thereof;

FIG. 3 is an elevational view of the side opposite that shown in FIGURE 1;

FIG. 4 is a bottom plan view thereof; and

FIG. 5 is an elevational view of the end opposite that shown in FIGURE 1.

The dominant features of our design reside in the portion shown in full lines.

We claim:

The ornamental design for a carrying case, substantially as shown and described.
